CLAIM

The ornamental design for a pressure transmitter housing, as shown and described.

DESCRIPTION

FIG. 1 is a front elevational view of a pressure transmitter housing embodying my new design;

FIG. 2 is a right side elevational view thereof;

FIG. 3 is a top plan view thereof;

FIG. 4 is a rear elevational view thereof;

FIG. 5 is a left side elevational view thereof;

FIG. 6 is a bottom plan view thereof;

FIG. 7 is a right side elevational view of a modified form of the transmitter with coplanar flange embodying our new design the left side being a mirror image; and

FIG. 8 is a rear elevational view of FIG. 7.

The broken line showing in the drawings are for illustrative purposes only and form no part of the claimed design.

FIG. 1

FIG. 2

FIG. 4

FIG. 5

FIG. 5

FIG. 7

FIG. 8
